United States Patent Office

Des. 195,524
Patented June 25, 1963

195,524

PIE DISH

George Patton, Jr., Warwick, R.I., assignor to Haveg
Industries, Inc., Wilmington, Del., a corporation of Delaware

Filed May 8, 1962, Ser. No. 70,040

Term of patent 14 years

(Cl. D44—15)

Fig. 1.

Fig. 2.

Fig. 3.

Fig. 4.

The bottom of the dish is substantially flat.

I claim:

The ornamental design for a pie dish, as shown and described.
